UNITED STATES PATENT OFFICE.

JOHN O. McKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

CREEL.

Application filed November 11, 1925. Serial No. 68,368.

For convenience in handling and for conservation of floor space and saving in expense, it is extremely desirable that the cops be mounted in their creels as closely together as possible. Heretofore, where cop holders have been made reversible to bring them to the inside of the creel for doffing, the holder supporting bars have been rocked on axes beyond the base ends of the holders, thereby requiring a considerable space to be left between the several rows of cops, to permit the cop holders of one row to swing the cops past the cop holder supporting bar of the next row in their movement to and from their doffing position.

The object of my present invention is to so construct and adapt the reversible cop holder supporting bars of the creel that they will rock the cop holders on axes extending through the cops between their inner and outer ends, preferably about midway between their ends, thereby allowing the rows of cops to be placed nearer together than heretofore possible in this type of creel, without interfering with their reversing movement.

A practical embodiment of my invention is represented in the accompanying drawings, in which—

Fig. 1 represents a detail top plan view of the creel with the cops shown in full lines in their running or non-doffing positions and in dotted lines in their doffing positions.

Fig. 2 represents a vertical transverse section taken in the plane of the line II—II of Fig. 1, looking in the direction of the arrows.

Fig. 3 represents a detail side view of the creel and a diagrammatic end view of a warping machine.

Fig. 4 represents a detail vertical transverse section on an enlarged scale, the cop, the cop holder and the cop holder supporting bar being shown in full lines in their running positions and in dotted lines in their doffing positions.

Fig. 5 represents a horizontal section taken in the plane of the line V—V of Fig. 4, looking in the direction of the arrows. 50

Fig. 6 represents a detail section taken in the plane of the line VI—VI of Fig. 4, looking in the direction of the arrows, showing the means for automatically locking the cop holder supporting bar in its running position. 55

The creel illustrated herein has a pair of converging racks, each made up of suitably placed longitudinal, vertical and cross bars 1, 2 and 3 respectively, the two racks being 60 properly tied together by suitably placed cross rods 4.

The cops 5 are arranged in a plurality of vertical rows, the holders 6 for each vertical row of cops being carried by a vertically disposed supporting bar 7, pivoted in the creel rack to rock on an axis extending through the cops between their ends, to reverse their positions for doffing. In the present instance each cop holder supporting bar 7 is 70 provided with upper and lower horizontal and parallel arms 8 and 9, pivoted in the creel rack to permit the bar to rock on a vertical axis extending through the vertical 75 rows of cops about midway between their ends, thus allowing the supporting bars to be placed much nearer together than where the bars were rocked on axes located beyond the base ends of the cop holders, as heretofore practiced. This close spacing of the 80 supporting bars either conserves floor space with a predetermined number of cops or else allows a greater number of cops to be placed within a predetermined space, as found 85 more desirable.

The means which I have shown for automatically locking the cop holder supporting bar in its running position is as follows:

The upper arm 8 of the bar 7 not only rocks but is vertically slidable on a depending pin 10 and the lower arm 9 not only rocks but is vertically slidable on the up-rising pin 11. This uprising pin 11 is carried by a segment 12 which supports the cop

holder supporting bar as it is rocked to and from its running and doffing positions. This segment 12 is provided with uprising stops 13 and 14 for limiting the rocking movement 6 of the cop holder supporting bar as the bar reaches its doffing and running positions respectively. The top face of this segment adjacent to the stop 14 has an inclined wall recess 15 into which the arm 9 drops for 10 automatically locking the cop holder supporting bar in its running position.

In moving the cop holder supporting bar to its doffing position the arm 9 will first ride up the inclined wall of the recess 15 and then 15 along the top of the segment until the arm strikes the stop 13.

Each yarn as it leaves its cop passes spirally around a vertically disposed bar 16 which acts to keep the yarn comparatively 20 taut whether the yarn is running or at rest. From thence the yarn passes through a tension device 17 on its way to the warping machine represented diagrammatically at 18.

What I claim is:—

- 25 1. In a creel, a cop, and an outwardly projecting free ended cop holder therefor pivoted to rock on an axis extending through the cop between its ends, to reverse its position for doffing.
- 30 2. In a creel, a cop, and an outwardly projecting free ended cop holder therefor pivoted to rock on a vertical axis extending through the cop between its ends, to reverse its position for doffing.
- 35 3. In a creel, a cop, a free ended cop holder, and a supporting bar from which the cop holder projects outwardly, pivoted to rock on an axis extending through the cop between its ends, to reverse its position for doffing.
- 40 4. In a creel, a cop, a free ended cop holder, and a vertically disposed supporting bar from which the cop holder projects outwardly, pivoted to rock on a vertical axis 45 extending through the cop between its ends, to reverse its position for doffing.

5. In a creel, cops arranged in a row, and outwardly projecting free ended cop holders therefor pivoted to rock on an axis extending through the cops between their ends, to reverse their positions for doffing.

6. In a creel, cops arranged in a vertical row, and outwardly projecting free ended cop holders therefor pivoted to rock on a vertical axis extending through the cops between their ends, to reverse their positions for doffing.

7. In a creel, cops arranged in a row, free ended cop holders, and a supporting bar 60 from which the cop holders project outwardly, pivoted to rock on an axis extending through the cops between their ends, to reverse their positions for doffing.

8. In a creel, cops arranged in a vertical 45 row, free ended cop holders, and a verti-

cally disposed supporting bar from which the cop holders project outwardly, pivoted to rock on a vertical axis extending through the cops between their ends, to reverse their positions for doffing.

70

9. In a creel, cops arranged in a plurality of rows, free ended cop holders, and a plurality of supporting bars from which the cop holders project outwardly, pivoted to rock on axes extending through the cops between 75 their ends, to reverse their positions for doffing.

10. In a creel, cops arranged in a plurality of vertical rows, free ended cop holders, and a plurality of vertically disposed supporting bars from which the cop holders project outwardly, pivoted to rock on vertical axes extending through the cops between 80 their ends, to reverse their positions for doffing.

85

11. In a creel, a pair of converging racks, cops arranged in a plurality of rows, free ended cop holders, and a plurality of cop holder supporting bars from which the cop holders project outwardly, pivoted in said 90 racks to rock on axes extending through the cops between their ends, to reverse their positions for doffing.

95

12. In a creel, a pair of converging racks, cops arranged in a plurality of vertical rows, 95 free ended cop holders, and a plurality of vertically disposed cop holder supporting bars from which the cop holders project outwardly, pivoted in said racks to rock on vertical axes extending through the cops 100 between their ends, to reverse their positions for doffing.

105

13. In a creel, cops arranged in a vertical row, free ended cop holders, a vertically disposed supporting bar from which the cop 105 holders project outwardly, pivoted to rock on an axis extending through the cops between their ends, to reverse their positions for doffing, and means for automatically locking the supporting bar in its running 110 position.

110

14. In a creel, cops arranged in a plurality of vertical rows, free ended cop holders, a plurality of vertically disposed supporting bars from which the cop holders project 115 outwardly, pivoted to rock on vertical axes extending through the cops between their ends, to reverse their positions for doffing, and means for automatically locking the supporting bars in their running positions.

115

15. In a creel, a pair of converging racks, cops arranged in a plurality of rows, free ended cop holders, a plurality of cop holder supporting bars from which the cop holders project outwardly, pivoted in said racks to 120 rock on axes extending through the cops between their ends, to reverse their positions for doffing, and means for automatically locking the supporting bars in their running 125 positions.

130

16. In a creel, a pair of converging racks, cops arranged in a plurality of vertical rows, free ended cop holders, a plurality of vertically disposed cop holder supporting bars from which the cop holders project outwardly, pivoted in said racks to rock on vertical axes extending through the cops between their ends, to reverse their positions

for doffing, and means for automatically locking the supporting bars in their running 10 positions.

In testimony, that I claim the foregoing as my invention, I have signed my name this 9th day of November, 1925.

JOHN O. McKEAN.
